GARMENT HOOK

Raymond A. Magnuson, Hinsdale, Ill., assignor to Vogel-Peterson Co., Elmhurst, Ill., a corporation of Illinois

Filed Sept. 10, 1965, Ser. No. 86,932

Term of patent 14 years

(Cl. D33—8)

FIG. 2 is a side elevation thereof.

FIG. 3 is a view like FIG. 1 but showing a modified form of the hook of FIGS. 1 and 2, the same having garment hanger stem receiving slots in the hook arms.

In each of the foregoing figures, mounting of the garment hook embodying my novel design upon an appropriate supporting plate has been indicated, for illustrative purposes only, with the plate being shown in fragmentary phantom outline.

I claim:

The ornamental design for a garment hook, as shown and described.
